HYDRAULIC JACK FOR THE TENSIONING AND ANCHORING OF THE REINFORCEMENT METAL IN A REINFORCED CONCRETE CONSTRUCTION Jacques Jean Bernard Joseph Jerome Bouvy and
Albert Komijn, The Hague, Netherlands

Application July 30, 1953, Serial No. 371,272

Claims priority, application Netherlands July 30, 1952

6 Claims. (Cl. 254—29)

The invention relates to a hydraulic jack for the tensioning and anchoring of the reinforcement metal in a reinforced concrete construction with pre-tensioned reinforcement comprising a cylinder with a main piston and an auxiliary piston. With this jack the wires of the reinforcement are adjusted in pairs in a slot arranged in the cylinder surface by means of wedges, whereby the main piston supports against an anchoring-block. Then liquid is supplied under pressure in a space between the main piston and the cylinder, causing a displacement of the cylinder with respect to the anchoring block and the wires are tensioned. Then liquid is brought under pressure into said space between the main piston and the auxiliary piston and so the auxiliary piston presses the anchoring plug into the anchoring block, anchoring in this way the wires of the reinforcement. At last the hydraulic pressure in the cylinder is let off and the tension in the reinforcement-wires extending from the anchoring block is relieved and the wires are loosened from the cylinder. This last manipulation is executed by means of a hammer, with the aid of which the wedges are beaten away, which has to be done by a skilled laborer, for, if perchance by a miss a wire is touched, there is a risk that the friction of the tensioned wire in the anchoring block is loosened by the fibrillation and the wire will lose part of its tension.

Another disadvantage of the jacks heretofore employed is the fact that the wires of the reinforcement located between the anchoring block and the wedges on the cylinder are contacting the extension piece of the main piston, causing an undesired friction during the tensioning of the wires.

Yet another disadvantage resides in the way of measuring the extension of the wires. Up till now this has been done by measuring the displacement of marks made on the wires before they are tensioned. This measurement of the displacement can take place only insufficiently by the means used up till now.

Another disadvantage is the possibility that by operating in improper sequence the taps through which the pressure fluid is supplied and withdrawn disturbing faults are made, for instance the anchoring of the wires before they are tensioned, and the like.

The invention has in view to meet the mentioned disadvantages.

According to the invention the jack is so constructed and provided with appliances that the successive manipulations of the tensioning of the wires of the reinforcement, the anchoring of the anchoring plug and the loosening of the wedges takes place automatically in the above-mentioned sequence.

According to another feature of the invention a ring shaped liquid chamber is arranged between the cylinder and the main piston, said liquid chamber is adapted to be brought in connection with the supply of the pressure-liquid so that the cylinder and the main piston can undergo a relative displacement as a result, the usual spring with the resulting friction losses can be eliminated.

According to another feature of the invention the liquid chambers in the jack are in communication with a controlling apparatus being so constructed that only one

2

of the chambers is in communication with the pressure liquid, the other chambers either being in open communication with the outlet of the liquid, or being closed off.

Other features and characteristics appear in the description and the claims.

The drawing, purely illustrative, represents one form of execution according to the invention, wherein the Figures 1—3 show, partially in section, three different stages of a jack with controlling apparatus during the action, and Figs. 4 to 10 are sectional views taken along lines 4—4 to 10—10 of Fig. 3, respectively.

The jack 1 comprises a cylinder 2, wherein a main piston 3 is axially movable. In an extension piece 4 with jackhead 42, firmly connected with the main piston 3 an auxiliary piston 5 is axially movable. In the jack three liquid or pressure chambers 6, 7 and 8 are provided, the liquid-chambers 6 being located between the top of the main-piston 3 and the end of the cylinder 2, the liquid chamber 7 being arranged ringshaped around the main piston 3 and limited by this main piston, the cylinder 2 and the walls 9 and 10 respectively of the cylinder and the main piston. The liquid chambers 6, 7 and 8 are by means of channels 11, 12 and 13 bored in the main piston or arranged otherwise in it, and by means of flexible tubes 14, 15 and 16 connected with the junction pieces 17, 18 and 19 on the cylinder 20 of the controlling device 21. The cylinder 20 is provided with a junction piece 22 for the supply of the pressure liquid and a junction piece for the outlet 23 of the liquid.

In the cylinder 20 a piston 24 is axially movable by a motor or the like (not shown), while four ringshaped chambers 25, 26, 27 and 32 being formed by peripheral ridges 29, 30 and 31 fitting in the innerwall of the cylinder. Chambers 28 and 33 are provided in the piston 24. The cylinder 2 is provided with a collar piece 34 with slots for the wire 35 of the cable and the wedges 36. On the main piston 3 a plurality of cams or ears 37, equal in number to the wedges 36 are arranged spaced at regular distances over the circumference of said main piston. These ears are preferably so arranged that their shock surfaces are placed staggered relative to each other, for instance so that always two ears extend radially opposite each other, having their shock surfaces in a plane perpendicular to the axis of the jack.

By this arrangement only two wedges 36 being located radially opposite each other are pressed away at the same time by a displacement of the main piston 3 with respect to the cylinder 2 to the right in the drawing, so causing a gradual relaxation of the wires.

The auxiliary piston 5 is movable in the extension piece 4 to the left, in the drawing, against the action of a spring 38.

The anchoring block is indicated at 39 and the anchoring plug at 40.

An elongation measuring device 41 is connected to the cylinder 2.

The device works as follows:

After the jack 1 with the jackhead 42 has been placed against the anchoring block 39 in the position shown in Figure 1, with plug 40 being mounted in the mouthpiece on the extension piece 4 and bearing loosely in the anchoring block 39, the wires 35 are fastened in the usual way in pairs by the wedges 36. The extension piece 4 is pressed against the anchoring block 39. In this phase the piston 24 of the controlling device is in its most right hand position. Now the piston 24 is brought in the position as indicated in Fig. 1, enabling the liquid to be pumped through the junction piece 22, the liquid chamber 25, the channel 28, the junction piece 17, the tube 14 and the channel 11 into the liquid chamber 6, causing the cylinder 2 to be moved with respect to the main piston 3, bearing against the anchoring block 39

in a direction away from this anchoring block, so tensioning the wires 35 of the cable. The degree of elongation can be accurately read on the elongation measuring device connected to the cylinder. This elongation has to correspond in accordance to the kind of steel, which is used, with the pressure read on the manometer of the liquid-pump.

When the desired elongation and the according pre-tension has been obtained, the piston 24 is moved to the left in the position as shown in Fig. 2. In this position the ridge 30 is laying in front of the junction 17, preventing the liquid under pressure in the liquid chamber 6 from flowing away so that the relative disposition of the piston 3 and the cylinder 2 remains unchanged. In this position of the piston 24 liquid is pumped via the junction 22, the liquid chamber 25, the channel 28, the liquid chamber 32, the junction 19, the tube 16 and the channel 13 into the liquid chamber 8 so pressing the auxiliary piston 5 against the pressure of the spring 38 in the direction of the anchoring block and so pressing the anchoring plug 40 firmly between the wires and anchoring them in the anchoring block.

Next the piston 24 is moved to the position as shown in Fig. 3. In the meantime the liquid in the chamber 6 is flowing away via the channel 11, the tube 14, the junction 17 and the chamber 26 and the liquid in the chamber 8 is flowing via the channel 13, the tube 16, the junction 19, the chamber 26 and both liquids are flowing together off through the channel 33 and the junction 23, pressure liquid is pressed via the junction 22, the chamber 25, the channel 28, the chamber 32, the junction 18, the tube 15 and the channel 12 into the liquid chamber 7, causing the walls 9 and 10 to be moved from each other and so displacing the main piston 3 into the cylinder 2. During this displacement the ears 37 approach the wedges 36 and press them under the influence of the liquid pressure without shock to the right, relaxing the wire ends behind the anchorage. Therefore every time two wedges located radially opposite each other are loosened simultaneously and in consequence of the staggering location of the shock surfaces, this loosening takes place pair after pair and consequently the relaxation is gradual.

What we claim is:

1. A hydraulic jack for tensioning and anchoring the wire reinforcement cable in a concrete construction with pre-tensioned reinforcement, which comprises: a main cylinder; a first chamber for liquid in said main cylinder; a main piston in said cylinder, an auxiliary piston slidably mounted in said main piston; an anchoring block and a cooperating anchoring plug for anchoring said tensioned reinforcement wires; means connecting said cylinder with said reinforcement wires, and said auxiliary piston with said anchoring plug, whereby movement of said cylinder relative to said main piston acts to tension said wires, and movement of said auxiliary piston relative to said piston serves to anchor said anchoring plug in said anchoring block, whereby said pre-tensioned wires are securely held; a further ring-shaped liquid chamber defined between the peripheral wall of a reduced portion of said main piston and the inner wall of said cylinder, said ring-shaped chamber being adapted to receive liquid pumped therein, said liquid chambers being in communication, whereby when liquid is pumped into said ring-shaped chamber and out of said first chamber in said main cylinder, said main piston is moved relatively to said main cylinder in a direction such that said main piston enters into said main cylinder and, at the same time, said auxiliary piston is loosened from said anchoring plug.

2. The hydraulic jack as defined in claim 1, wherein a plurality of wedges serve to fasten said wires to said main cylinder, and wherein means are provided for controlling, without possibility of error, the sequence of desired operations in said tensioning and anchoring,

said means controlling the flow of liquid to and from said liquid chambers in said main cylinder and said ring-shaped chamber whereby, upon moving said main piston in a single direction, the following sequence of operations occurs; first, said wires are tensioned; second, said wires are anchored; and third, said wires extending beyond said anchoring plug are loosened by removal of said wedges.

3. A hydraulic jack for tensioning a wire cable in a pre-tensioned structure, comprising in combination; a cylinder provided with slots for receiving the strands of said cable, a main piston extending into said cylinder and, defining therewith first and second chambers, admission of fluid into said chambers selectively effecting relative displacement between said cylinder and said main piston in opposite directions, an auxiliary piston defining a third chamber with said main piston, admission of a fluid into said third chamber effecting displacement of said auxiliary piston relative to said main piston, and first, second and third duct means communicating with said first, second and third chambers, respectively, for admission of a fluid thereinto and for exit of said fluid therefrom, whereby following disposition of said cable strands in said cylinder slots, admission of fluid into said first chamber effects tensioning of said strands, admission of fluid into said third chamber displaces said auxiliary piston relative to said main piston for anchoring said tensioned strands in said structure, and admission of fluid into said second chamber empties said first chamber for releasing the ends of said strands held in said slots of said cylinder.

4. A jack as defined in claim 3, in which said slots of said cylinder are set in balanced groups, said jack being further provided with wedges for holding said strands in said slots, and a cam member operatively connected with said main piston, said cam member being provided with ears corresponding in number and disposition to the slots of each cylinder group, whereby admission of fluid to said second chamber causes said ears to enter said slots and remove said wedges, the grouping of said slots ensuring an even release of tension on the ends of said cable strands.

5. A jack as defined in claim 4, in which each group is composed of two diametrically opposite slots, said cam member thus being provided with two diametrically opposite ears.

6. A jack as defined in claim 3, including control means for said duct means, said control means comprising a further cylinder and a further piston displaceable therein, said further cylinder being provided with inlet and outlet means for a fluid and with apertures communicating with said first, second and third duct means, respectively, said further piston controlling communication between said inlet and outlet means on the one hand and said apertures on the other hand, whereby displacement of said further piston within said further cylinder sequentially causes said first chamber to communicate with said inlet means to tension said strands, said third chamber to communicate with said inlet means to anchor said tensioned strands, and said second chamber to communicate with said inlet means while said first and third chambers communicate with said outlet means, to thereby fill said second chamber with fluid and empty said first and third chambers of fluid for releasing the ends of said cable strands held in the slots of said cylinder.
